H. A. BLOOMQUIST,
STARTING AND STOPPING MECHANISM FOR PHONOGRAFS.
APPLICATION FILED JAN. 28, 1920.

1,360,080.

Patented Nov. 23, 1920.

UNITED STATES PATENT OFFICE.

HELMER A. BLOOMQUIST, OF MANISTEE, MICHIGAN.

STARTING AND STOPPING MECHANISM FOR PHONOGRAHS.

1,360,080.

Specification of Letters Patent. Patented Nov. 23, 1920.

Application filed January 28, 1920. Serial No. 354,649.

To all whom it may concern:

Be it known that I, HELMER A. BLOOMQUIST, a subject of the King of Sweden, residing at Manistee, in the county of Manistee and State of Michigan, have invented certain new and useful Improvements in Starting and Stopping Mechanism for Phonographs, of which the following is a specification.

- 10 This invention relates to certain new and useful improvements in a device to be used for starting and stopping phonographs, and particularly that type of such instruments known as Edison phonographs, and it consists in certain peculiarities of the construction, novel arrangement, operation and combination of the various parts thereof, as will be hereinafter more fully set forth and specifically claimed.
- 20 The principal object of the invention is, to provide a starting and stopping mechanism for phonographs which shall be simple and inexpensive in construction, strong, durable and efficient in operation, with its parts so made and arranged that they can be readily applied to Edison phonographs of the diamond disk type without any material alterations in the construction thereof, and in such a manner that starting and stopping the operation of the instrument may be effected by lowering and raising, respectively, the reproducer onto or from the recreation disk or record.

Other objects and advantages of the invention will be disclosed in the following description and explanation.

In the accompanying drawing which serves to illustrate an embodiment of the invention—

- 40 Figure 1 is a view partly in section and partly in elevation of portions of the turn-table, supporting platform of an Edison phonograph and a part of the rod or shaft used for raising and lowering the reproducer, showing my improvements in the position thereon they will occupy after the instrument has been started.

Fig. 2 is a diagrammatical plan view of the mechanism showing by dotted lines the position the parts will occupy when the instrument is stopped thereby.

Figs. 3, 4 and 5 are detached perspective views of the locking and releasing member or lever, the brake-shoe carrying member

or lever and the operating member or lever, respectively.

Like numerals of reference refer to corresponding parts throughout the different views of the drawings.

The reference numeral 10 designates the turn-table which is mounted for rotation, in the usual or well known way, directly above the supporting platform 11 of a phonograph and has at its periphery a downwardly extended flange 12 for coöperation with the brake-shoe of the mechanism as will be presently explained. At a suitable distance from and within the circle described by the flange 12, the platform 11 is provided with an opening 13 for the reception and operation of certain upright parts of the device.

Pivoted and horizontally mounted on a pivot 14 seated in the platform 11 outwardly from the opening 13 therein is the brake-shoe carrying member which comprises a bell crank lever 15 the outwardly extended arm 16 of which is provided at its free end with a holder 17 for a plug 18 of felt or other suitable material which holder and plug extend outwardly from the arm 16 and constitute the brake-shoe of said member. The other or inwardly extended arm 19 of the bell lever has at its end opposite the pivot 14 an extension 20 depending through the opening 13, and provided at its lower end with a horizontally disposed and outwardly directed arm 21 to the free end of which is hinged one end of a member 22, which is normally held in alinement with the member 21 by means of a spring 23 secured at its inner end to the member 21. The adjacent ends of the members 21 and 22 are constructed in any suitable manner to prevent the member 22 dropping yet so as to permit its upward movement against the spring 23 when the arm 41 of the operating bell crank lever contacts with the shoe 24 of the member 22. The outer end of the member 22 is provided with a foot 24 disposed at an angle thereto and substantially in parallelism with the arm 16 of the bell crank lever. The arm 16 of said lever is provided with a depending projection 25 which is located at the juncture of said arm with the holder 17 and is preferably angular in shape as shown in Figs. 1 and 4 of the drawing.

100

5 Mounted on the upper surface of the platform 11 on a pivot 26 seated in said platform near the opening 13 therein is the locking and releasing member or lever of the device, which comprises a horizontally disposed arm 27 having fitted in an opening therein a headed bushing 28 which receives the upper portion of the screw or pivot 26 as is shown in Fig. 1 of the drawing. The 10 head 29 of the bushing 28 is slightly spaced from the arm 27 and said bushing has mounted thereon between the head and arm 27 an outwardly extended flat member 30 which is provided near its free end with an 15 opening 31 one of the walls of which is provided with a shoulder 32, see Fig. 3 of the drawing.

20 The arm 27 is provided near its free end with a transverse slot 33 through which is extended a set screw 34 which engages the member 30 and is used to secure it in the desired position with respect to the arm 27. Depending from the inner end of the arm 25 27 is an extension 35 which is located in the opening 13 and has at its lower end a horizontally and outwardly directed lever 36 which is provided at its free end with a vertical flange or foot 37 which is disposed angularly with respect to said lever. The 30 arm 27 is located below the bell crank lever and normally in such a position that the lever 36 will occupy a position substantially in parallelism with the arm 19 of the bell crank lever as will be readily understood by reference to Fig. 2 of the drawing, in which view it will be seen that the foot or flange 37 of the lever 36 is located near and in the path of one of the arms of the bell crank operating lever which is designated as a whole by the numeral 38 and is mounted on the rod or shaft 39 just below the platform 11 which rod or shaft is used for raising, lowering and adjusting the position of the reproducer and connected to 45 the latter for this purpose in the ordinary or well known way. The operating bell crank lever 38 comprises a tripping arm 40 which is by preference inwardly curved as shown, and a longer arm 41 which is also extended inwardly but at an angle to the shorter arm. These arms are fitted on a tube 42 which surrounds the post 39 and may be fixed thereto by means of a set screw 43 seated in said tube.

50 55 The free end of the arm 40 is provided with an enlargement 44 the upper surface of which is downwardly beveled or inclined as at 45 from that edge of the enlargement 44 opposite the shorter arm of the operating bell crank lever.

60 65 When the instrument is at rest, or before it has been started, the parts of the mechanism will occupy about the positions shown by dotted lines in Fig. 2 of the drawing, from which it will be seen that the plug 18

of the brake-shoe will be in contact with the inner surface of the flange 12 of the turn-table, and it will be understood that the arms 40 and 41 of the operating bell crank lever 38 will be in contact with the flange or foot 37 of the lever 36 and with the shoe 24 of the member 22 respectively. The parts of the bell crank lever 15 and of the locking and releasing member will be held in about the positions thereof shown by dotted lines in Fig. 2 by means of the spring 46 which connects the arm 19 of said lever to the member 30 of the locking and releasing member and by reason of the engagement of the projection 25 on the arm 16 70 75 80 with the outer end of the opening 31 in the member 30.

To release or start the instrument, it is only necessary to turn the handle 47 which is pivoted to the upper portion of the shaft 39 from the dotted line position thereof shown in Fig. 1 of the drawing, to the vertical position shown in said figure when it will be understood that the reproducer will be lowered so that the diamond will rest on the disk or record. This operation will also cause slight upward movement of the operating bell crank lever 38 and its arms, to the end that the beveled portion 45 of the arm 41 co-acting with the foot 24 on the hinged member 22 will cause said member to be raised against the tension of the spring 23 when by a slight rotary movement of the shaft 39 in the proper direction, the levers or the members 21 and 36 90 will be moved inwardly, thus permitting the projection 25 to engage the shoulder 32 of the opening 31 in the member 30 of the locking and releasing member. When in this position, the plug 18 of the brake shoe 100 will be held out of contact with the flange 12 of the turn table, as shown in Fig. 1, and thus permit rotation of said table and the 105 operation of the instrument.

Having thus fully described my invention, 110 what I claim as new and desire to secure by Letters Patent is—

115 In a device of the class described, the combination with the platform of a phonograph having a vertical opening therein, of a turn table rotatably mounted above the platform and having a downwardly extended peripheral flange, a reproducer adjusting shaft vertically journaled in the platform externally of the turn table, means on said 120 shaft to raise, lower and turn the same, a locking and releasing member pivotally mounted on the platform and carrying below the same a lever extended toward said shaft and provided with an angularly disposed foot, said member having in its portion above the platform an opening provided with a shoulder in one of its walls, 125 a bell crank lever pivotally mounted on the platform and carrying below the same a 130

horizontally disposed spring-actuated outwardly directed member having at its free end an angularly disposed foot, one of the arms of the bell crank lever having an outwardly extended brake shoe, said arm of said lever also having a projection located in the aforesaid shouldered opening, a spring uniting the other arm of said lever to said member, a bell crank operating lever

mounted on said shaft below the platform, 10 one of the arms of the last named lever adapted to contact with the foot of the spring-actuated member and provided with a beveled portion for co-action therewith and the other arm of said lever adapted to 15 contact with the foot on the lever of the locking and releasing member.

HELMER A. BLOOMQUIST.
